UNITED STATES PATENT OFFICE.

JOSEPH S. JUDGE, OF BROOKLYN, NEW YORK.

WAXER AND POLISHER.

Application filed March 26, 1925. Serial No. 18,648.

This invention relates to a waxing and floor polishing brush.

To properly wax and polish floors it is essential that a brush be used because of the slight irregularities of a wood floor to which only a brush will conform, in addition only a brush will smooth out the wax, and prevent uneven deposition thereof, due to the movement of the individual bristles. A waxing rag may be secured over the bristles and, if so done, the movement of the bristles forces the wax out of the rag in spite of the glazing of the rag's waxing surface. Such brushes have been made for a long time with short or long handles. The objection to the brushes has been that in the case of the short handle brush the user is obliged to kneel while polishing which makes the labor very much more tiresome and with the long handled brush it is difficult to exert the required amount of pressure. The brushes have been weighted but in such cases the center of gravity being high they have a tendency to turn over and the weight striking the floor or furniture causes denting and scratching.

One of the objects of this invention is to provide a waxing brush with the point of application of the pressure exerted by the user below the center of gravity of the weighted brush in order to avoid the tripping over of the brush when in use. Still another object of the invention is to provide removable weights for the brush. A further object of the invention is to provide means for securing a waxing cloth over the bristles of the brush to apply the wax. Other objects of the invention will appear more fully hereinafter.

40 Referring to the drawings:

Figure 1 is a plan view of a device embodying the principles of my invention.

Figure 2 is a longitudinal sectional view of Figure 1 along the line 2, 2, looking in the direction of the arrows.

Figure 3, is a cross sectional view of Figure 1, along the line 3, 3, looking in the direction of the arrows.

50 1 is the base or body of the brush having bristles 2 secured therein in the usual manner. Around the exterior of the body 1, I propose to provide a felt or rubber covering 3 to prevent injury to any furniture or woodwork in case the brush is struck against the same. A casting 5 is secured by bolts 4 to body 1. Casting 5 is formed in a hollow

square. Centrally in the base of the side walls of casting 5 are cylindrical ends 7 of casting 8, which latter is threaded to receive wood handle 9. Such construction permits of quick assembly and enables the user of the brush to make longer strokes as the handle is permitted to pivot to a lower angle by reason of the U shaped ends, of casting 5.

Upon the top of body 1, I provide four pointed pins 10 which have sloping holes or chambers 11 in weight 12 to receive said pins, the base of weight 12 is supported longitudinally by feet 13. The function of the feet 13 is to permit a cloth 14 to fit under the weight 12 and over the pins 10 in the chambers 11. The pins 10 hold the cloth 14 from withdrawal. Weight 12, also, is adapted to fit around casting 5 and is cut out at one end to permit weight 12 to be removed by lifting it from casting 5, against the action of springs 16, and by turning the weight 12 through a 90 degree angle to pass the narrow side of casting 8 through the opening in the end of weight 12. The casting 8 must be held perpendicular to permit removal of the weight. Should springs 16 become weak, such construction prevents the weight in case of accidental dislodgment from falling off the brush onto the floor and marring its surface. The other end of weight 12 may be grooved so that the handle may pivot to a sharp angle with the body 1 of the brush. Weight 12 has cut out notches 15 to receive springs 16, said springs 90 being fastened between casting 5, and base 1, of the brush. Pressure of springs 16 will hold weight 12, in a rigid position on the brush.

I have referred to various parts of the 95 device as castings but I do not desire to be limited to such use or manufacture as forgings might just as well be used.

It will therefore be seen that I provide a very simple efficient floor waxing or polishing brush wherein the weights may be varied to suit the occasion for instance, when applying the wax the weight to be used is twenty-five pounds while when polishing a 7 or 8 pound weight will be substituted. It 105 will also be noticed that the center of pressure exerted by the user is centrally of the brush and below the center of gravity of the weight and therefore the brush is practically untiltable and will not injure the 110 floor. The brush is of few parts, easily assembled and cheap to manufacture.

What I claim is:

A brush comprising bristles, a base for said bristles, a casting secured to said base, a handle pivotally secured to said base by 5 said casting, a removable weight on said base surrounding said casting, said handle being of narrow width adjacent the pivotal connection, one side of said weight having a narrow slot, said slot being of a greater

width than that of said handle adjacent the 10 pivotal connection to permit of removal of the weight when raised and rotated through an angle of ninety degrees.

Signed at New York in the county of New York and State of New York this 2nd day 15 of March A. D. 1925.

JOSEPH S. JUDGE.
